Langlotz Patent & Trademark Works, LLC**ABSTRACT**

An explosive initiator retention assembly comprises a pair of opposed shell elements. The shell elements have a pair of spaced-apart passages, each configured to receive an elongated initiator having a cylindrical form. Each passage has a rotation inhibitor element configured to rotationally engage an initiator, such the initiators are retained against rotation.

DUAL INITIATOR COUPLER KIT**CROSS-REFERENCE TO RELATED APPLICATIONS**

This application claims the benefit of U.S. Provisional Patent Application No. 63/013,461, filed on Apr. 21, 2021, entitled "DUAL INITIATOR COUPLER KIT", which is hereby incorporated by reference in its entirety for all that is taught and disclosed therein.

FIELD OF THE INVENTION

The present invention relates to igniters.

BACKGROUND AND SUMMARY

M81 igniters are commonly used to initiate the shock tube or M700 Time Fuse of MDI (modern demolitions initiative) blasting caps when breaching walls, doors, etc.

As a failsafe, end users often install two MDI blasting caps next to each other. This is a time-intensive process involving taping them together securely.

The above disadvantage is addressed by an explosive initiator retention assembly that comprises a pair of opposed shell elements. The shell elements have a pair of spaced-apart passages, each configured to receive an elongated initiator having a cylindrical form. Each passage has a rotation inhibitor element configured to rotationally engage an initiator, such the initiators are retained against rotation.

BRIEF DESCRIPTION OF THE DRAWINGS

FIG. 1 shows the D.I.C.K closed, encasing two igniters, and ready for instant use.

FIG. 2 shows the D.I.C.K. consists of two symmetrical hard bodies (A) hinged together with a length of 1" One

2

Wrap webbing (B). The One Wrap webbing is designed to wrap around both bodies and to fasten back onto itself in order to securely encase two M81 igniters. Note the texture located on the internal surface of Part A to help prevent rotation of the M81 igniters during their initiation.

FIG. 3 shows technical drawings of the two symmetrical hard bodies of Part A from numerous angles and sides, while empty.

FIG. 4 shows technical drawings of the two symmetrical hard bodies encasing the ignitor devices, including: a broad-side view; a narrow side-view; a view from the top; an angled view from slightly above; and a cross-section.

DETAILED DESCRIPTION OF A PREFERRED EMBODIMENT

15

M81 igniters are commonly used to initiate the shock tube or M700 Time Fuse of MDI (modern demolitions initiative) blasting caps when breaching walls, doors, etc.

As a failsafe, end users often install two MDI blasting caps next to each other. This is a time-intensive process involving taping them together securely.

The Dual Initiator Coupler Kit (D.I.C.K) allows users to quickly secure two ignitors in the correct position for breaching needs.

I claim:

1. An explosive initiator retention assembly kit comprising;
  - a pair of opposed shell elements hingedly coupled together;
  - the shell elements together defining a pair of spaced-apart passages each configured to receive an elongated initiator having a cylindrical form; and
  - each passage defining a rotation inhibitor element configured to rotationally engage an initiator, such the initiators are retained against rotation.
